W. E. COOK ET AL.

INSULATED WIRE MAKING MACHINE

Filed Nov. 20, 1917

UNITED STATES PATENT OFFICE.

WILLIAM E. COOK, OF ST. GEORGE, NEW YORK, AND MERRITT B. BRADT, OF PENNINGTON, NEW JERSEY, ASSIGNEES TO PEERLESS INSULATED WIRE AND CABLE COMPANY, OF NEW YORK, N. Y., A CORPORATION OF DELAWARE.

INSULATED-WIRE-MAKING MACHINE.

Application filed November 20, 1917. Serial No. 203,056.

To all whom it may concern:

Be it known that we, WILLIAM E. COOK, a subject of the King of the United Kingdom of Great Britain and Ireland, residing at St. George, in the borough of Richmond, city of New York, county of Richmond, and State of New York, and MERRITT B. BRADT, a citizen of the United States, residing at Pennington, in the county of Mercer and State of New Jersey, have invented certain new and useful Improvements in Insulated-Wire-Making Machines, of which the following is a specification, reference being had therein to the accompanying drawings, which 15 form a part thereof.

Our invention relates to insulated wire making machines, and more particularly to a machine for making insulated wires, the exterior of which is protected by a braid and 20 the insulation of which is formed of cotton sliver or other similar absorbent, fibrous material saturated or impregnated with asphaltum or other like composition.

Heretofore in the manufacture of insulated wire of this character it has been the practice to spirally wind cotton sliver or other material upon the conductor wire and after the application of this material to the wire, to run the covered wire through an ordinary braiding machine to apply the braided covering thereto. While applying the cotton sliver or other material to the wire in the winding machine, the sliver or other material is closely compacted about the wire 35 and held in this compacted condition by any desired means as a thread wound about the same, the compacting being accomplished by passing the wire with the sliver wound about it, through a forming die or horn. 40 Since in wire made as above described, the sole bond between the cover braid and the insulating material results from the adhesiveness of the asphaltum or other composition, continued use, or abrasion, results in a 45 complete separation of the braided covering from the body of the insulation.

By means of a machine made in accordance with our invention, we are enabled to inclose a conductor wire with cotton sliver or other absorbent, fibrous material, and ap-

ply a covering braid to the covered wire, by a single, continuous operation in one and the same machine. This manner of making the wire results in the more or less loose fibres of the cotton sliver or other material, 55 being enmeshed with the crossed threads forming the braid, thus causing a firm interlock between the meshes of the braid and the fibrous material of the insulating body. The construction of the machine is such that 60 the compaction of the sliver, or other material, will result in part from the application of the strands forming the braid thereto, and in part, by a forming die or horn 65 acting upon the braid-covered wire immediately after the application of the braid thereto.

We have found that a better entangling of the strands of the cover braid and the outer fibres of the covering of cotton sliver, or 70 other material, is secured by shortening the angle of the strands with relation to the axis of the wire at the point of application of these strands thereto.

To ensure uniformity in the thickness and 75 resulting density of the insulating cover for the wire, we have found it essential in a machine made in accordance with our invention, to so construct the machine as to maintain the same relation between the bare wire 80 and the cotton sliver, or other material, irrespective of bends in the wire, which particularly with heavier wires, are almost unavoidable.

The invention consists primarily in a machine for making insulating wire, embodying therein means adapted to impart lineal traverse to a wire, means adapted to lay a strip of fibrous material longitudinally thereof upon said wire, a braiding mechanism adapted to apply a plurality of braided strands about said fibrous material, and a compacting die arranged beyond said braiding mechanism through which the covered wire passes, whereby outer fibers of said material will be enmeshed with the crossed strands of the braid thus formed and said fibrous material will be compacted upon and about the wire; and in such other novel features of construction and combination of 95 100

parts as are hereinafter set forth and described and more particularly pointed out in the claims hereto appended.

Referring to the drawings:

Fig. 1 is a front view of a machine embodying our invention, partly in section and partly in elevation; and

Fig. 2 is a plan view of the table of the braiding mechanism and of the means for laying the fibrous strips upon the wire and for maintaining the proper relative position of said means and the wire.

Like letters refer to like parts in both of said views.

In the embodiment of our invention shown in the drawings, *a* indicates the table of an ordinary braiding machine having therein a central opening *a'*, the braiding mechanism *b* carried by which, is old and well known in this art and therefore shown more or less diametrically and in fragmentary manner in the accompanying drawings. The construction and mode of operation of this braiding mechanism is immaterial to our invention as any desired braiding machine may be used which is capable of applying a tubular braid to a continuous strand. The actuating mechanism *c* for the braiding needles and the spools or cops, is positioned between the table *a* and the fixed table *d* supported above and spaced away from the said table *a*. The table *d* has a central opening *d'* therein in axial alinement with the opening *a'*. Carried by a suitable cross head *e* is a grooved wheel *f* driven at a low, uniform rate of speed from a shaft *g* by the gear train *g'*. The wheel *f* is the same as that ordinarily employed in braiding machines for covering insulated wires, for accurately positioning the wire *h* within the various braiding needles *b*. The construction heretofore described is old and well known in this art, and it is not our intention to claim any of this mechanism broadly as a part of our invention, since a machine embodying the characteristics above described, is now in common and extensive use in applying the cover braid to various types of insulating wire.

Our invention resides in the combination with a braiding machine such as we have described, or with any other similar braiding machine, of certain mechanisms by which the functions of this machine may be modified in a manner to apply a fibrous covering to a wire and inclose said covering within the braid formed by the machine in a particular manner to secure a more uniform and more permanent union between the body of the insulating material and the braided cover than is possible to secure with the old type of braiding machine alone.

With this end in view, we provided the table *d* with a guide block *j* having a

truncated conical opening therethrough, the base of which opening is in substantial register with the opening *d'*. This guide block *j* is adapted to have passed through the opening therein a plurality of strips *k* of cotton sliver, or other material, which material is laid upon the wire *h* above the guide block *j* as a result of the movement of said wire *h* and the wheel *f*.

Above the guide block *j* is a forming die or horn *m* supported from the main frame of the braiding machine, through which the wire after the braid has been applied thereto is drawn, the different strands *n* forming the braid being applied to the wire just prior to its passage through said die or horn *m*. In order to secure a better enmeshing of the various strands *n* with the outer fibres of the strips *k*, or a more thorough entangling of said fibres and the meshes of the braid, we provide the forming die or horn *m* with a bell mouth presented toward the guide block *j* so as to vary the angle of application of said strands *n* and force them into the body of the strips *k* before they are drawn taut to compact said strips *k* about the wire *h*. By this construction the tightening of the braid about the cover wire occurs at a point above that at which the strands *n* first engage the strips *k*, thus permitting the formation of the mesh about the fluffy fibres of said strips *k* and the closing or tightening of the mesh while some of said fibres are inclosed thereby. Furthermore, this construction results in the compaction of the fibrous strips *k* in part by the strands *n* and in part by the die or horn *m*. The manner of applying the braid also tends to wrap the strips *k* entirely about the wire, to facilitate which we preferably employ a plurality of said strips *k* disposed about the wire.

We have secured highly satisfactory results by using two strips *k* laid upon diametrically opposite surfaces of the wire *h*, although, it is not our intention to limit ourselves to the use of two such strips. Between the guide block *j* and the die or horn *m*, we provide a hollow guide *o* through which the wire *h* passes. The guide *o* is supported from the guide block *j* in axial alinement with the opening through said block so as to preserve the proper relative positions of the strips *k* and the wire *h*. The outer surface of the guide *o* is in the form of a truncated cone so as to guide the strips *k* in relation to the wire *h*, said strips being laid upon said wire above said guide.

Owing to the liability of the wire *h* to have bends therein, we preferably mount the guide block *j* upon the table *d* in a manner to permit a universal movement of said block upon a single plane, so that

- 5 said block is capable of movement under the control of the guide *o* carried thereby, to accord with any irregularities or bends in the wire, the simultaneous movement of said guide and said guide block *j* preserving the relative position of the strips *k* and the wire *h* irrespective of a departure of the wire from a straight line at any point thereof. To permit this movement of the guide 10 block *j*, we mount it upon the plate *d* by means of headed studs *p* passing through circular openings in the guide block *j*, the diameter of which openings is greater than that of said studs. The quantity of movement 15 resulting from the bends in the wire is never great, so that the slight lost motion afforded by this manner of mounting the guide block *o* is enough to compensate for any such bends in the wire.
- 20 The studs prevent any substantial lifting of the guide block *j*, while permitting a free sliding movement of the block upon the table *d*.

25 The strips *k* are coiled in containers *q* in a manner to permit them to be drawn freely therefrom.

30 The machine of our present invention has no relation to the saturation or impregnation of the covering for the wire which ordinarily is done by a subsequent operation.

35 The operation of the herein described machine is substantially as follows:—

A wire *h*, drawn from a reel of wire (not shown) is passed through the openings *a'*—*d'* and the openings in the guide block *j*, the guide *o* and the forming die or horn *m* and about the grooved wheel *f* to a rewinding mechanism (not shown) but commonly used in connection with a braiding machine. The wheel *f* is driven at a slow uniform rate of speed, thus maintaining the wire in the proper relation to the braiding and other mechanisms during its slow 40 lineal traverse. When starting the machine, the ends of the strips *k* are drawn from the containers *q*, passed through the openings *a'*—*d'* and the opening in the guide block *j*; about the guide *o* and secured to the wire below, but within, the forming die or horn *m* so that movement 45 of the wire *h* will impart similar movement to the strip *k*.

50 The ends of the strands *n* are then secured to the wire in the usual manner and power is applied to the braiding mechanism *b*. The number of strands *n* varies in different machines, these strands being so interwoven in the operation of the machine, as to secure the desired mesh.

55 In placing the ends of the strands about the portion of the strips *k* laid upon the wire at and within, the forming die or horn *m*, said strands will engage the edge of the bell mouth of this die or horn, which will

vary the angle of said strands, and cause the application of the tension or stresses upon said strands to be applied to the covered wire within the die or horn. The outer edge of this bell mouth will define the initial crossing points of the separate strands *n* thus causing the outer fibres of the strip *k* which are adjacent and project beyond, the inner wall of said bell mouth to be entangled in the mesh of the braid and to be 70 tightly grasped thereby in a manner to form a firm and permanent interlock between these fibres and the braid with the subsequent closing of the mesh and resultant compacting of the covering for the wire. 75 In this manner, the braid is bonded firmly to the fibrous covering for the wire, so that wear of the braid from abrasion, or otherwise, will not result in the separation of the braid from the compacted strips *k*, the 80 saturation of the braid and the fibrous material of the strips serving merely to add greater permanency to the union between the braid and the cotton sliver or other material of the insulating covering. 85

90 In the event of the wire *h* having bends therein, such irregularities in the wire will displace the guide *o* according to the direction of said bend, thus imparting movement to the guide block *j* in accord with change 95 of direction of projection of the wire due to such bends. This movement of the guide block *j* will cause the strips *k* to follow the wire irrespective of bends therein and thus preserve the relative position of the wire and said strips under all conditions. 100

105 A machine made in accordance with our invention, applies the fibrous material directly to the wire, forms the fibrous material while applying the outside braid thereto, secures the desired degree of compaction of this material and unites the braid to said fibrous material. These results are all secured by a continuous operation of the machine under the same conditions present in 110 an ordinary braiding machine, thus avoiding the necessity for dividing the production of insulated wire of this character into two distinct operations and effecting a saving of the strand or other means used for binding the spirally wound cotton sliver, or other material, upon the wire in order 115 to permit its being properly fed through the braiding machine.

120 By laying these strips *k* directly upon the wire *h* as described, and compacting them during the application of the braid thereto, these strips are relieved from the longitudinal stresses incidental to winding them spirally about the wire, thus avoiding likelihood of frequent breakages of the sliver, or the necessity for guarding against such breakages in the production of said sliver. Furthermore, in a machine of our invention, the cotton sliver, or other material, is 125 130

incorporated in the insulated conductor wire by a mechanism very much simpler, than that ordinarily employed for applying such material to the wire while the manner of applying the sliver minimizes any tendency of its separating from the wire in the event of the cutting of the braid.

Since the fibres of the cotton sliver, or other material, will lie substantially longitudinally of the wire, the stripping of the wire during installation is comparatively easy as compared with a wire having a spirally wound insulating covering.

It is not our intention to limit the invention to the details of construction shown in the accompanying drawing, it being apparent that such may be varied without departing from the spirit and scope of the invention.

Having described our invention what we claim as new and desire to have protected by Letters Patent is:—

1. A machine for making insulated wire embodying therein means adapted to impart only lineal traverse to a wire, non-rotary means adapted to guide a strip of matted fibrous material substantially parallel with, and lay it longitudinally of, and upon, said wire, a braiding mechanism adapted to apply a plurality of strands to said fibrous material, and a compacting die arranged beyond said braiding mechanism in the direction of movement of the wire, whereby the meshes of the braid-forming strands will enmesh or entangle therein, outer fibers of said fibrous material, and said material will be compacted upon or about the wire substantially simultaneously with the application of the strands of the braid thereto without winding said fibrous material spirally about the wire.

2. A machine for making insulated wire embodying therein means adapted to impart only lineal traverse to a wire, a non-rotary block having an enlarged opening therethrough through which a wire and a strip of matted fibrous material pass in substantially parallel relation, a braiding mechanism adapted to apply a plurality of strands to said fibrous material, and a stationary forming die or horn beyond said braiding mechanism whereby the braid is applied to the strip covering the wire prior to its passage through said die or horn, and outer fibres of said material will be enmeshed or entangled in the meshes of the braid thus formed and said fibrous material will be compacted upon and about the wire without being wound spirally about same.

3. A machine for making insulated wire embodying therein means adapted to impart only lineal traverse to a wire, a non-rotary block having an enlarged opening therethrough through which a wire and a strip of matted fibrous material pass in substan-

tially parallel relation, a braiding mechanism adapted to apply a plurality of strands to said fibrous material, and a stationary forming die or horn beyond, and having a bell mouth presented toward said braiding mechanism, said braiding mechanism applying the braid to said strip prior to its passage through said die or horn, whereby outer fibres of said material will be enmeshed or entangled in the meshes of the braid thus formed and said fibrous material will be compacted upon and about the wire without being wound spirally about same.

4. A machine for making insulated wire embodying therein means adapted to impart lineal traverse to a wire, a non-rotary block having an enlarged opening therethrough through which a wire and a strip of fibrous material pass in substantially parallel relation, a braiding mechanism adapted to apply a plurality of strands to said fibrous material, means whereby said block may have universal movement on a single plane, means operatively connected with said block and adapted to be engaged by the wire, whereby the relative position of the wire and the strip of fibrous material will be at all times substantially the same, and a stationary forming die or horn above said last named means, said braiding mechanism applying the braid to said strip prior to its passage through said die or horn.

5. A machine for making insulated wire embodying therein means adapted to impart lineal traverse to a wire, a non-rotary block having an enlarged opening therethrough through which a wire and a strip of fibrous material pass in substantially parallel relation, a braiding mechanism adapted to apply a plurality of strands to said fibrous material, means whereby said block may have universal movement on a single plane, a hollow guide supported by, movable with and having the opening therein axially aligned with the opening of, said guide block, and adapted to have the wire pass therethrough and the strip of fibrous material to pass thereabout, whereby the relative position of the wire and the strip of fibrous material will be at all times substantially the same, and a stationary forming die or horn above said hollow guide, said braiding mechanism applying the braid to said strip prior to its passage through said die or horn.

6. A machine for making insulated wire embodying therein means adapted to impart lineal traverse to a wire, a non-rotary block having an enlarged truncated, conical opening therethrough through which a wire and a strip of fibrous material pass in substantially parallel relation, a braiding mechanism adapted to apply a plurality of strands to said fibrous material, means whereby said block may have universal

- movement on a single plane, a truncated, conical, hollow guide supported by, movable with and having the opening therein axially alined with the opening of, said guide block and adapted to have the wire pass therethrough and the strip of fibrous material to pass thereabout, whereby the relative position of the wire and the strip of fibrous material will be at all times substantially the same, and a stationary forming die or horn above said hollow guide, said braiding mechanism applying the braid to said strip prior to its passage through said die or horn.
7. A machine for making insulated wire embodying therein means adapted to impart lineal traverse to a wire, a non-rotary block having an enlarged truncated, conical opening therethrough through which a wire and a strip of fibrous material pass in substantially parallel relation, a braiding mechanism adapted to apply a plurality of strands to said fibrous material, means whereby said block may have universal movement on a single plane, a truncated, conical, hollow guide supported by, movable with and having the opening therein axially alined with the opening of, said guide block and adapted to have the wire pass therethrough and the strip of fibrous material to pass thereabout, whereby the relative position of the wire and the strip of fibrous material will be at all times substantially the same, and a stationary forming die or horn above, and having a bell mouth presented toward, said hollow guide, said braiding mechanism applying the braid to said strip prior to its passage through said die or horn.
8. A machine for making insulated wire embodying therein means adapted to impart only lineal traverse to a wire, non-rotary means whereby a strip of matted fibrous material is guided in parallel relation to and laid longitudinally of the wire, a braiding mechanism adapted to apply a tubular braid about said fibrous material, and compacting means arranged beyond said braiding mechanism and having a circular flaring mouth presented toward same whereby the strands forming said braid are brought into engagement with the fibrous material at one angle and the angle of said strands is thereafter varied to maintain them in engagement with the fibrous material of said strip as said strip is being folded about and compacted upon the wire, whereby fibres of said material are enmeshed or entangled in the meshes of said braid.

In witness whereof we hereunto affix our signatures in the presence of two subscribing witnesses this 29th day of Oct., 1917.
